UNITED STATES PATENT OFFICE.

SAWYER D. CLARK AND CHARLES F. BARTELL, OF BOULDER, COLORADO.

VACUUM-PRODUCING DEVICE.

973,405.

Specification of Letters Patent. Patented Oct. 18, 1910.

Application filed October 25, 1909. Serial No. 524,587.

To all whom it may concern:

Be it known that we, SAWYER D. CLARK and CHARLES F. BARTELL, citizens of the United States, residing at Boulder, county 5 of Boulder, and State of Colorado, have invented certain new and useful Improvements in Vacuum-Producing Devices; and we do declare the following to be a full, clear, and exact description of the invention, such as will enable others skilled in the art to which it appertains to make and use the same, reference being had to the accompanying drawings, and to the letters and figures of reference marked thereon, which 10 form a part of this specification.

Our invention relates to improvements in vacuum producing devices, our object being to provide a construction adapted to be connected with a faucet through which water is 20 drawn for household purposes, the ordinary system pressure only being employed.

Our improved device consists of a pipe connected with the faucet and extending downwardly a suitable distance, its lower extremity being closed and having openings above the bottom of the closure to allow the water to escape. In our improved construction a hood or shield is applied to the discharge pipe and adapted to surround the 25 portion of the pipe containing the openings, whereby the water is prevented from spreading over a large area. This hood confines the water and causes it to pass downwardly 30 into the sink, or other apparatus through which it may make its escape to the sewer. Connected with this discharge pipe is a conduit leading to the vacuum cleaner nozzle which engages the article from which the dirt or dust is to be removed. The upper 35 extremity of the discharge pipe, as shown in the drawing, is provided with a removable nozzle which extends downwardly adjacent the opening with which the cleaner conduit 40 is connected.

Having briefly outlined our improved construction, we will proceed to describe the same in detail, reference being made to the accompanying drawing, in which is illustrated an embodiment thereof.

In this drawing: Figure 1 is a view illustrating our improved apparatus shown in condition for use. Fig. 2 is a sectional view, of the discharge pipe and its connections shown on a larger scale.

The same reference characters indicate the same parts in all the views.

Let the numeral 5 designate a fixture which, as shown in the drawing, has a threaded connection, as shown at 6, with the faucet 7. The threaded part 6 is rotatably applied to the member 5 but when tightly screwed thereon, the discharge end of the faucet may engage the upper extremity 8 of the ejector nozzle 9 which protrudes downwardly into the member 10 of the part 5. This nozzle 9 is threaded into the upper extremity of the pipe member 10, adjacent the junction of the member 12 with the member 10. Connected with the part 12 is the flexible conduit 13 whose opposite extremity is connected with the cleaner nozzle 14.

The lower extremity of the fixture 5 has a threaded connection, as shown at 15, with the upper extremity of the discharge pipe 16, to whose lower extremity is applied a sort of cup 17, which is threaded on the pipe extremity, as shown at 18. The lower part of this cup is closed, while its upper portion adjacent the end of the discharge pipe 16, is open to permit the escape of the water after filling the cup 17.

It is evident that a great variety of specific constructions may be employed in carrying out our improvement. The construction illustrated in the drawing, however, has proven satisfactory in actual use.

Applied to the discharge pipe 16 and surrounding the apertured portion of the cup 17, is a shield 19 which has the shape of an inverted cup, its upper extremity having a collar 20 which fits closely to the exterior of the pipe 16 and is held in place thereon by a thumb bolt or screw 21. This shield is vertically adjustable on the pipe 16, since the collar is slidable on said pipe and may be locked by the set bolt 21 in any position of adjustment.

When the device is in use, the faucet is opened, whereby the water is allowed to enter the member 10 of the fixture 5 and pass downwardly into the cup 17 which rapidly fills, the water then escaping through the openings in the upper part of the cup. It is evident that in the absence of a shield or housing, the water would be discharged in all directions, through the openings 22. With the shield in place, however, the water issuing from the openings 22 striking against the walls of the inverted cup-shaped shield 19, will be guided downwardly into a sink 23 provided with a pipe 24 leading to

the sewer. It is evident that the water may be discharged into any suitable receptacle, the latter being preferably connected with the sewer to facilitate the escape of the water.

5 We have found from actual experience and demonstration, that it is of the utmost importance to have a cup or closure applied to the lower extremity of the discharge pipe, whereby the escape of the water from the 10 discharge pipe will produce the necessary suction for cleaning purposes. It has been found in practice, that the discharge pipe without a cup or closure connected with its lower extremity will not result in giving the 15 necessary suction pull for cleaning purposes. However, by the use of the cup having openings in its upper portion, whereby a sort of trap is formed, the suction is very strong and gives excellent results. This is apparently due to the fact that the water backs up 20 in the cup 17, and in combination with the shield, or inverted receptacle 19, either actually seals the lower extremity of the discharge pipe 16, or causes the water to escape 25 therefrom with sufficient force, to prevent the entrance of air to break the suction. The breaking of the suction due to the entrance of air at the lower extremity of a discharge pipe seems to be the difficulty experienced in 30 employing the ordinary open-ended pipe for suction purposes. It is found in actual practice that the shield or inverted cup 19 so arranged that its lower edge projects below the openings 22 in the closure 17, is necessary 35 in order to obtain an effective suction for working purposes. When so arranged ten inches vacuum is obtained, with approxi-

mately one hundred pounds water pressure, as indicated by the vacuum gage; while with the shield or inverted cup omitted, no vacuum is indicated by the same gage, when the same water pressure is used. 40

Having thus described our invention what we claim is:

As an article of manufacture for domestic use, a vacuum producing device adapted to be attached to a water spigot and to receive water under pressure, said device comprising an ejector having a discharge pipe whose upper end is adapted to be connected with the spigot, and has a branch pipe for connection with an air tube, and whose lower end is equipped with an enlarged closure which curves outwardly from the pipe, the upper portion of the closure being perforated for the escape of water discharged from the pipe thereinto, and the dome shaped hood or shield open to the atmosphere at its lower end for the free escape of the water, the hood being applied to the pipe and surrounding the closure in such proximity thereto that the water issuing from the perforations of the closure is controlled so as to produce a suction effect, in the space between the hood and closure substantially 55 as described.

In testimony whereof we affix our signatures in presence of two witnesses.

SAWYER D. CLARK.
CHARLES F. BARTELL.
